UNITED STATES PATENT OFFICE

WALTER A. SCOTT, OF POUGHKEEPSIE, NEW YORK, ASSIGNOR TO THE DE LAVAL SEPARATOR COMPANY, OF NEW YORK, N. Y., A CORPORATION OF NEW JERSEY

CLEANSING COMPOSITION

Application filed May 26, 1928. Serial No. 280,954.

No Drawing.

My invention relates to cleansing compositions and particularly to that class of cleansing compositions ordinarily called soap powders.

5 The object of my invention is to provide a cleansing composition of high efficiency for general use and particularly of maximum efficiency for cleansing dairy equipment, including pails, cans, milking machines, etc.

10 The requirements for such a composition are that it will quickly remove dried fat and casein and that it may be easily completely rinsed off so that no objectionable film or stain will remain. It is also necessary that

15 it shall have no injurious effects on aluminum, tin, steel or rubber.

A composition embodying my invention and accomplishing the foregoing objects comprises trisodium phosphate objects (Na₃PO₄ + 12H₂O), sodium metasilicate (Na₂SiO₃·9H₂O), soap, preferably a sodium soap (NaC₁₂H₂₂O₂), and soda ash (Na₂CO₃).

A less efficient cleanser may be made without the soda ash.

25 The proportion of trisodium phosphate may vary from 30 to 50 per cent, but is preferably between 35 and 45 per cent.

The proportion of sodium metasilicate may vary from 40 to 60 per cent., but is preferably between 35 and 45 per cent.

30 The proportion of soap may vary from 2 to 10 per cent., but is preferably between 3 and 8 per cent.

The proportion of soda ash should not exceed 10 per cent and preferably should not exceed 8 per cent, the most desirable proportion being about 5 per cent.

A specific composition which is preferred for the purpose of cleansing dairy equipment comprises trisodium phosphate about 40%, sodium metasilicate about 50%, soap about 5% and soda ash about 5%.

If the soda ash is omitted, or is added in much reduced proportion, the preferred percentages of the other ingredients, particularly of the trisodium phosphate and the sodium metasilicate, should be correspondingly increased. Thus, if the soda ash be omitted, a specific preferred composition would comprise trisodium phosphate about 42%, sodium

metasilicate about 53% and soap about 5%.

For certain purposes, a good cleanser can be made containing the specified ingredients in proportions outside even the maximum ranges specified; but for general purposes and particularly for cleansing dairy equipment, the ingredients specified should be the ranges of proportions specified.

55 The addition of a minor proportion of other material is permissible, but in such case, while the relative preferred proportions of the ingredients specified should be maintained, their absolute proportions should be reduced in accordance with the proportion of other materials that may be added.

60 The relative proportions specified are based on weight.

What I claim and desire to protect by Letters Patent is:

1. A composition for cleansing dairy equipment containing trisodium phosphate, sodium metasilicate and soap in about the following relative proportions: trisodium phosphate 32-52%, sodium metasilicate 42-62% and soap 2-10%.

75 2. A composition for cleansing dairy equipment containing trisodium phosphate, sodium metasilicate, soda ash and soap in about the following relative proportions: trisodium phosphate 30-50%, sodium metasilicate 40-60%, soap 2-10%, and not over 80 about 10% of soda ash.

3. A composition for cleansing dairy equipment containing trisodium phosphate, sodium metasilicate and soap in about the following relative proportions: trisodium phosphate 37-47%, sodium metasilicate 47-57% and soap 3-8%.

85 4. A composition for cleansing dairy equipment containing trisodium phosphate, sodium metasilicate, soda ash and soap in about the following relative proportions: trisodium phosphate 35-45%, sodium metasilicate 45-55%, soap 3-8% and not over about 90 8% of soda ash.

95 5. A composition for cleansing dairy equipment containing trisodium phosphate, sodium metasilicate and soap in about the relative proportions of 42% of trisodium 100

phosphate, 53% of sodium metasilicate and 5% of soap.

6. A composition for cleansing dairy equipment containing trisodium phosphate, sodium metasilicate, soda ash and soap in about the relative proportions of 40% of trisodium phosphate, 50% of sodium metasilicate and 10% of soda ash and soap.

In testimony of which invention, I have hereunto set my hand, at Poughkeepsie, New York, on this 23d day of May, 1928.

WALTER A. SCOTT.
